(57) **CLAIM**

(21) Appl. No.: **29/164,943**

The ornamental design of a sidewall detail for a beverage bottle, as shown and described.

(22) Filed: **Aug. 2, 2002**

DESCRIPTION

(51) LOC (7) Cl. **09-07**
(52) U.S. Cl. **D9/434**; D11/90
(58) Field of Search D11/1, 2, 26-29,
D11/89-92; 63/26-28, 32; D20/37; D9/516,
307, 320, 434

FIG. 1 is a front view of a sidewall detail for a beverage bottle.

FIG. 2 is an enlarged front view of the sidewall detail for a beverage bottle, of FIG. 1.

FIG. 3 is a right side view of the sidewall detail for a beverage bottle, of FIG. 2, taken along the line III—III FIG. 2, the left side view of which is a mirror image thereof
FIG. 4 is a bottom view of the sidewall detail for a beverage bottle, of FIG. 2, taken along the line IV—IV FIG. 2, the top view of which is a mirror image thereof; and,
FIG. 5 is a rear view of the sidewall detail for a beverage bottle, of FIG. 2.

The dotted lines illustrate environmental structure and do not form part of the design.
